UNITED STATES PATENT OFFICE.

HARRY AUGUSTUS LEDYARD AND JAMES JULE JELLEY, OF ASHLAND, OHIO.

VAULT OR THE LIKE.

Application filed April 3, 1922. Serial No. 548,955.

To all whom it may concern:

Be it known that HARRY AUGUSTUS LEDYARD and JAMES JULE JELLEY, citizens of the United States of America, residing at 5 Ashland, in the county of Ashland and State of Ohio, have invented certain new and useful Improvements in Vaults or the like, of which the following is a specification.

This invention relates to burial vaults.

10 The primary object of this invention is to construct a burial vault of several parts, which are formed of plastic material and adapted to be assembled together to provide an air sealed enclosure for caskets or the like.

15 A further object of the invention is to provide a vault for enclosing burial caskets or the like, by constructing the vault of a plurality of parts so as to admit of ease and convenience in handling, and less weight in 20 assembling the parts of the vault, transporting and depositing the parts in the grave, and assembling the parts therein to complete the vault.

25 A further object is to provide means of constructing a vault of several parts to enclose and support a casket therein at a predetermined point above the ground to prevent water from coming in contact with the casket.

30 Another object of the invention is to so construct and form the different parts of the vault so as to equalize the weight of the parts to facilitate and permit the parts to be deposited in the grave and assembled 35 therein without making it necessary to lift or handle excessive weight.

35 A further object is to construct a foundation for the vault that will permit convenient and expeditious bailing out of water 40 accumulated in the grave.

45 A further object is to provide a vault that can be made of a minimum number of parts and quickly and rapidly assembled by unskilled labor, thereby saving labor and material.

These and other objects are attained by the mechanism illustrated in the accompanying drawings in which:—

Fig. 1 is a side elevation of the invention 50 partly in section showing a casket enclosed therein.

Fig. 2 is the bottom plan view of the foundation of the vault.

Fig. 3 is a perspective view of a casket 55 supporting member.

Fig. 4 is an end elevation of part of the cover.

In the drawings, reference numerals 1, 2, 3, and 4, represent the side and ends of the foundation, which are preferably made 60 rectangular in form, leaving a rectangular opening (5) in the center thereof. The edges surrounding or adjacent to the opening (5) are rabbeted to provide shouldered grooves to receive one or more casket supporting members (6) which are provided with spaced apart ribs (7 and 8) and arranged at right angles to the side of the supporting member.

65 The supporting members (6) are preferably made of such a width as to slidably fit within the rabbeted side portions of the foundation. In order that the weight of the parts may be equalized, it is preferable to use in the construction of the vault two or 70 more supporting members as shown in Fig. 1, and indicated by reference numerals 6.

75 If desired, the supporting members (6) can be made of different lengths so as to leave more or less space as indicated at 11, 80 between the ends thereof, to permit the casket supporting members to be slidably moved for adjustment, on the rabbeted portions of the foundation.

85 The ribs (7 and 8) which are used for the purpose of maintaining and supporting the casket, are spaced apart leaving a space, as indicated at 12.

90 The foundation is preferably made of a pre-determined thickness, that is, such a thickness as will admit rabbeting of the sides and ends, adjacent to the opening as herein below described, and to hold and maintain the supporting member or members spaced 95 above the ground, as indicated at 13.

100 This arrangement permits of considerable water percolating from the ground into the space before reaching a height sufficient to contact with the bottom of the sliding members.

105 The space 13, also permits the assembler of the vault to bail out the water accumulated in the grave, with ease and convenience, before the casket is put into place. The foundation, supporting members, and combined cover and body portion are re-inforced by apertured or meshed sheet metal or the like as shown at 14.

110 In order to provide means for depositing the supporting members upon the rabbeted

portions of the foundation, an aperture (15) is provided in each of the supporting members through which a strap or the like is inserted for the purpose of lifting, holding, 5 conveying, and handling the supporting member when it is desired to deposit and assemble the parts upon the foundation.

In order to provide means of assembling the combined cover and body portion, which 10 is represented by reference numeral 17, one or more handles (18) are provided and attached to the combined cover and body portion through the medium of screws (19) or the like.

15 Straps can be inserted under the handle, or the handle can be grasped by the hand of the assembler if desired, for the purposes of lifting and depositing the combined cover and body portion of the vault upon the 20 foundation.

An ordinary casket is represented by reference numeral 20. (See Fig. 1.) In the drawings two casket supporting members are shown, which is the preferable 25 method of construction and use. It will be observed, however, that one or more supporting members can be used if desired, without departing from the principle of the invention, or if desired, one or more ribs 30 can be provided on each of the supporting members.

Attention is called to the fact that all of the parts are designed to be molded of concrete, cement, or other plastic material, and 35 when made of such material, are efficient, durable, and practical for the purpose intended. It will be apparent, however, that the structure can be made up and assembled of other than plastic material without departing from the principle of the invention.

If desired, prior to the assembling and mounting the combined cover and body portion of the vault on the foundation, cement, mortar, or the like can be plastered 45 over the foundation on the top of the sides and ends, thereby sealing and locking the parts together.

It is not necessary, however, to seal or cement the parts together to carry out the 50 objects of the invention as close contact is secured by permitting the bottom of the combined cover and body portion to contact with the top portion of the sides and ends of the foundation without the insertion of cement or the like.

It will be noted that in constructing a vault as herein described that all the parts can be molded and each one separately deposited in the grave. In practice, the 55 foundation is first inserted in the grave, then the slidable supporting members are mounted to slide over rabbeted portions of the foundation for adjustment, to conform to any size casket, then the cover and body portion is placed upon the foundation en-

closing the casket and supporting members.

Attention is called to the fact that the ribs (7 and 8) are made of such a height as will support the casket above the air sealing point of the bottom of the cover and 70 foundation.

We claim:

1. In a vault, an integral foundation having an opening therein and rabbeted around said opening, a supporting member adapted 75 to be slidably mounted on said rabbeted portion of the foundation, lugs having apertures formed in the upper portion thereof and an integral hollow body composed of a top, sides and end portions mounted 80 on the foundation in spaced relation from the sliding supporting member as for the purpose described.

2. In a vault, an integral hollow member 85 composed of sides, a top and end portions, a rectangular foundation member having an opening formed therein which is rabbeted around said opening, members adapted to be supported on the rabbeted portion of the foundation and also being provided, 90 with upwardly projecting integral members, said foundation member being adapted to support the hollow body without interfering with the members.

95 3. In a vault, a foundation member comprising a rectangular slab having an opening formed thereon and rabbeted around the opening, removable supporting members adapted to be fitted to and mounted on said rabbeted portion of the foundation, said removable supporting members having apertured rib portions formed thereon for the purpose of supporting a casket or the like and a cover comprising a top, end and side portions adapted to rest upon said foundation to form an entire hollow closed member, as and for the purpose described.

100 4. In a vault, a foundation comprising a slab having an opening formed therein, said foundation being rabbeted around said opening, slidably removable members adapted to be supported on said rabbeted portion of the foundation and a hollow member adapted to be supported on the foundation 105 without interfering with the slidable members, as and for the purpose described.

110 5. In a vault, an integral member, comprising a top, sides and ends, a foundation member comprising a slab having an opening therein and being rabbeted around said opening, and removable supporting members having apertured projections formed on the top and adapted to be slidably supported on the rabbeted portion of said foundation, as and for the purpose described.

115 6. In a vault comprising the following parts, an integral hollow enclosure comprising a top, sides and end members, a slab foundation having an opening therein and rabbeted around said opening, removable 120

members fitted to said rabbeted portion and supported thereon, ribs provided on the removable members, as and for the purpose described.

5 7. In a vault the combination of an integral hollow closure member with a slab having an opening therein to provide a foundation for the closure member, remov-

able supports adapted to be supported on the foundation and having apertured projections formed thereon. 10

In testimony whereof we affix our signatures.

HARRY AUGUSTUS LEDYARD.
JAMES JULE JELLEY.
